APPARATUS FOR FORMING PULP ARTICLES

Ernest Huff, Rockford, Ill., and Andrew Keiding, Milwaukee, Wis., assignors to American Lace Paper Company, Milwaukee, Wis., a corporation of Wisconsin

Application December 2, 1935, Serial No. 52,484

19 Claims. (Cl. 92—54)

This invention relates to improvements in apparatus for forming pulp articles. The present application is a companion to the patent of Ernest Huff and Andrew Keiding, No. 2,023,200, issued December 3, 1935, for improvements in the Art of molding pulp containers.

The present application pertains to apparatus constituting one means for the practise of the process therein disclosed.

10 It is the object of the invention to provide novel and improved pulp molding apparatus capable of operating upon pulp blanks for the manufacture of containers of practically any desired form.

15 More specifically, it is my object to provide improved means for handling the wet pulp blanks during, before and after, the forming operation; to provide improved means for holding the blanks to a predetermined size and form; 20 to compress the blanks while protecting the pulp against unduly localized pressure such as would destroy the fibers and the felting thereof; and to substantially eliminate rubbing such as would likewise destroy or reduce the waterproof or 25 other desirable characteristics of a container made in accordance with the disclosure of the companion process application above identified.

In the drawings:

30 Figure 1 is a side elevation of the operative portions of mechanism embodying the invention as they appear when exposed by the removal of a portion of the frame and actuating connections.

35 Figure 2 is a view in elevation showing the opposite sides of the mechanism illustrated in Fig. 1.

Figure 3 is an end elevation of the mechanism shown in Figs. 1 and 2.

40 Figure 4 is a detail view in section on an enlarged scale showing the portion of the cam mechanism by which the mandrel shafts are tilted.

45 Figures 5, 6, 7, and 8 are detail views on an enlarged scale illustrating partially in section and partially in front elevation the successive positions of the mandrel, the forming die, and the work.

50 Figure 9 is a view similar to Fig. 7 showing a modified embodiment of the invention.

Figures 10, 11, and 12 are detail views showing in elevation the several cams used to control the function of the parts.

55 Figure 13 is a fragmentary detail view in plan showing the drive for the mandrels.

Like parts are identified by the same reference characters throughout the several views.

The machine includes any appropriate frame such as that indicated at 14 through which extends the upper flights of conveyor chains 15.

5 The wet pulp blanks 16 containing preferably fifty to fifty-five percent of free water, are transported by trays 17 from the molding apparatus to the conveyor 15. In the device as illustrated, each tray carries 20 blanks. The conveyor is actuated to advance the trays with a step by step movement, and in each dwell a tray is registered within the frame 14 beneath the mandrel carriage 18 which is rotatably mounted 10 in the frame.

15 The mandrel carriage 18 is polygonal in form, and from each of its faces projects a series of mandrels 19 corresponding in number to the blanks of each tray.

The individual mandrels 19 have vents 21 20 opening to their peripheries as indicated in Fig. 5. These vents are inadequate in size or number to withdraw any appreciable amount of water from the pulp during the forming operation, it being our intention to compress the pulp 25 without permitting the extraction of water therefrom to any great degree. The vacuum, however, holds the pulp to the mandrel, thereby preventing it from shifting thereon or increasing the size with respect thereto during the forming 30 operation. The individual mandrels may preferably also be heated as indicated by the resistance coils 22 (Fig. 5). The coils may be supplied with current by means of slip rings 23 and 24 on the hub of each mandrel and brushes 25 and 35 26 coacting therewith during the rotation of the mandrel on the stud 27 projecting from the face of carriage 18. The brushes in turn are carried with similar slip rings at 28 and 29 on the end of carriage 18 supplied with current from any suitable source through the brushes 30 and 31.

40 The vacuum and pressure alternately applied through the ducts 21 are provided for by the pipe-like bearings 27 which place the interior of each mandrel in communication with the interior 45 of carriage 18 and the stuffing box 32 (Fig. 3) with which the supply line 33 connects. The application and control of pressure and vacuum through rotary parts is well known, and since the details are not important to the present invention they will need no further description.

45 At each dwell of the conveyor chains 15 the transfer carriage 35 will be sharply lifted twice by means of the cam 36 and rocker arms 37 and 38. In its first upward movement the transfer 50 55

carriage will encounter the wet pulp blanks 16 to free them from their tray 17 and to lift them, and ultimately the tray, toward the rotary mandrel carriage 18. At this point the mandrels are 5 subject to vacuum and the wet blanks in registry therewith will adhere to the mandrels. The tray and transfer carriage 35 will then be lowered and the mandrel carriage 18 will be 10 rotatively indexed ninety degrees to bring a group of 15 formed articles 40 into registry with the empty tray.

The elevator 35 is now raised for the second time to lift the tray to a position where it can receive the completed articles 40 from the mandrels. The interiors of the several mandrels which are downwardly presented at this time are 15 temporarily subjected to pressure instead of vacuum to effect the discharge of the articles 40 therefrom on to the tray. The next advance of 20 the conveyor chains 15 moves the tray full of completed articles out of the frame and substitutes therefor another tray of wet blanks. While the articles 40 are referred to as complete, it will be understood that they have still to be 25 dried, since practically no water is normally squeezed therefrom during the operations herein referred to.

The initial upward movement of the elevator 35 is effected by the broader lobe of cam 36 to give a 30 dwell of sufficient duration for the vacuum to become effective to hold the blanks to the mandrels. The second lift of the elevator is effected by the shorter lobe of cam 36 because no particular time is required for the discharge of the 35 formed articles into the tray. In both upward movements of the elevator the elevator may conveniently be counterbalanced as shown.

Only the articles on the mandrels at the top of carriage 18 in any given position of rotative adjustment thereof are worked upon. The mechanism for forming the articles is as follows.

There is a sub-frame 45 vertically slidable upon the rails 46 and including horizontal cross heads at 47 and 48. Extending therebetween are the 45 spindle shafts 49. At its lower end each of the spindles 49 carries a die 50. These dies correspond generally in number and position to the mandrels 19, but in addition to the relative vertical or axial movement between the several dies 50 and several mandrels provided for by slide 45, there is also a swinging or pendular movement of the spindles 49 which is utilized in the adjustment of the dies 50 in a lateral direction with respect to the several mandrels.

Fig. 4 shows the lower cross head 47 upon which the bearing blocks 51 of the several spindles 49 are laterally adjustable in suitable guideways. The outer side faces of the blocks 51 are beveled, and the push rods 53 which are transversely reciprocable are provided with cams 54 acting on the bearing blocks to push them inwardly and thereby to displace the dies 50 carried by the respective spindles 49.

The push rods 53 in turn are engaged by the 65 actuators 56 and 57 which carry cam followers 58 and 59 operated upon by the cams 60 and 61 respectively. The cams 60 are the ones which effect the lateral movement of the dies, and the cams 61 effect the release of the dies so that gravity 70 will restore them to a normal vertical position.

The timing of the movement of the parts is indicated in Figs. 5, 6, 7, and 8. Each die 50 is laterally displaced in the course of its downward movement on to the work, so that it engages the 75 work with a simultaneous rolling and drawing

action. While the action is referred to as being a rolling action, it will be understood that this is accomplished without localized compression of the pulp since the die and the mandrel are so nearly the same diameter (see Fig. 6).

The angle of the side wall of the inner surface of the die is slightly greater than that of the side wall of the exterior periphery of the mandrel, so that the surfaces engaged in the compression of the pulp at one side of the mandrel will be approximately parallel in a vertical direction when the die is laterally displaced as shown in Fig. 6. As explained in the companion application aforesaid, the slight drawing action produced by the relative movement illustrated in Fig. 5 displaces 15 a certain amount of material toward the larger end of the pulp blank which is there available for filling the grooves of the die to create the embossed effect illustrated. Since heat is desirable in the completion of the article the dies, as well 20 as the mandrels, may preferably be equipped with electrical resistance coils at 62, or with some other suitable heating devices. The apparatus may be successfully employed, however, without heat, if desired.

By the compression without localized pressure as shown in Fig. 6 under the thrust of the cams 54 which laterally displace the bearing blocks 51 and the dies 50, we complete the forming of the article 40 from the blank 16. Thereupon the 20 cams 61 effect the release of the camming elements 54 and bearing blocks 51 to allow the pendular movement of the spindles 49 to restore by gravity the dies 50 to their normal position of axial registration with the mandrels. The dies 35 are now entirely clear of the completed articles 40 and the return reciprocation of the slide 45 lifts each die clear of the article upon which it is operated, thereby leaving the carriage 18 free for a further indexing movement.

The construction shown in Fig. 9 is merely illustrative of the fact that devices of special form may be made on this apparatus. So far as is known, it has not heretofore been possible to form an article having cylindrical walls. The article 400 illustrated in Fig. 9 is a can of molded pulp with a straight tubular or cylindrical wall, the opposite sides of which are entirely parallel. Obviously such a can may, on the present apparatus, be made as deep or shallow as required. 45 Since a slight divergence is required between the inner periphery of the die 500 and the work so that the die will be parallel with the work when pushed laterally as shown in Figs. 6 and 9, the inner periphery of the die is slightly frustoconical but the angle is necessarily somewhat exaggerated in Fig. 9 in order to illustrate this point.

The pendular movement of the spindles 49 is so slight that it does not materially interfere 60 with the mesh of the gears 65 at their upper ends whereby all spindles are driven at the same speed.

The mandrels 19 may be so mounted as to idle upon their tubular supporting shafts 27, but preferably the mandrels are also driven at a peripheral speed very closely approximating that of the dies. The driving connections are as follows:

Carried by the vertically reciprocable slide 45 are the bracket arms 66 which support a table 67 upon which we mount the motor 68, the speed reducer 69 on the gearing which drives shafts 70 and 71. Shaft 70 moves with the slide and table and carries a pinion at 72 meshing with one of the gears 65 for the rotation of all of the 75

spindles 49 concurrently. Shaft 11 is mounted on the frame 14, and its driving pinion 73 is carried by the table and splined to the shaft to transmit movement to the shaft in all positions 5 of the slide. The shaft 11 operates a pulley 14 which co-operates with pulley 75 to support a belt 76. In each indexed position of the rotary mandrel carriage 18 a disk 77 mounted on the corner mandrel is presented to the belt in friction contact therewith to receive motion from the belt as shown in Figs. 1, 3 and 13. Gears mounted on all the mandrels as shown at 78 transmit motion from one to another so that all are driven from belt 76 by disk 77 in unison with 10 the dies 50 (or 500).

In this particular apparatus the vertical reciprocation of the slide is effected hydraulically. There is a hydraulic cylinder at 79 and the piston rod 80 is connected with the slide. The synchronous movement of the slide is subject to the control of a valve, of which 81 is the casing and 82 is the valve rod. The valve rod is operated by a tension spring 83, a lever 84, cam follower 85, and cam 86, the latter being mounted on the 20 drive shaft 87. The drive shaft may be belt operated from motor 88 (Fig. 3).

Adjacent valves 89 and 90 control the vacuum and air connections to the mandrels and are operated by levers 91 and 92 respectively. The 30 lever 91 is subject to the tension of spring 93 and carries cam follower 94 engaged by cam 95, shaft 87. The lever 92 is subject to the tension of spring 96 and carries cam follower 97 subject to the action of cam 98 on said shaft.

35 The cams 60 and 61 which shift the dies laterally with respect to the mandrels and the work, derive their motion from shaft 87 through chain 100, shaft 101, bevel gearing 102, cross shaft 103, chain 104, and cross shaft 105.

40 The cam 36 which operates the elevator 35 receives its motion from the drive shaft 87 through chain 107.

The rotatable mandrel carriage receives its indexing movement and the conveyor chains 15 receive their intermittent advance from a duplex Geneva motion. The rotary mandrel carriage 18 is mounted on a tubular shaft 108 through which extends an inner shaft 109. The Geneva gears 110 and 111 are mounted on shafts 108 and 109 45 respectively, and are spaced apart to receive the single Geneva pinion disk 112 which has a tooth peg 113 projecting from one of its faces and a like peg 114 projecting from the other of its faces at a diametrically opposite point on the disk. 50 Despite the fact that the Geneva motion is duplex, using a single pinion disk, its operation is conventional. The peg 113 operates the Geneva gear 111 in alternation with the operation of Geneva gear 110 by peg 114. Thus, each of the 55 shafts 109 and 110 are alternately advanced ninety degrees. Shaft 110 delivers its motion directly to the mandrel carriage 18 mounted thereon, while shaft 109 is connected by a chain 115 with the drive sprocket which actuates the conveyor 15.

60 The operation of the machine will now be briefly reviewed:

The conveyor 15 carries trays 17 in the direction indicated by the arrow in Fig. 1. When 65 these trays are placed upon a conveyor they contain wet pulp blanks 16. In the step by step advance of the conveyor these blanks are positioned beneath the lowermost mandrels 19 on the indexing mandrel carriage 18. The elevator 70 35 moves upwardly to dislodge the blanks from

the trays and to thrust them upon the mandrels. The mandrels are simultaneously subjected to vacuum which holds the cups in place thereon, the dwell of the elevator being sufficient to assure opportunity of the vacuum to act on the blanks. 75

During this operation the blanks carried by the mandrels which are uppermost on the indexing carriage 18 are being worked upon by the dies 50. These dies have descended over the blanks and at the same time have been pushed 10 laterally out of registry with the mandrels as shown in Fig. 5 by the mechanism illustrated in Fig. 4. The dies and mandrels are preferably but not necessarily heated, and they are so nearly the same diameter that the lateral pressure of 15 the die upon the work is not localized, but is distributed over the surface of the work. As the die moves downwardly and during its operation in its position of full engagement with the work, it is continuously rotated and the mandrel is 20 preferably, but not necessarily, rotated at the same time and at approximately the same peripheral speed so as to avoid any substantial rubbing between the die and the work. The vacuum is continuously applied to the mandrel 25 to hold the work thereto. The die has a flare or angle of side which deviates slightly from the side of the mandrel so that in the inclined position of the die its surface which contacts the work will be parallel to the underlying portions of 30 the mandrel as shown in Fig. 6.

Before the die ascends to free the work for rotation with the indexing carriage 18, the lateral pressure upon the die is relieved and the die swings into concentricity with the mandrel as 35 shown in Fig. 7, so that it may be drawn straight off the work without contact therewith, as shown in Fig. 8.

The mandrel carriage 18 is now indexed to move the completed articles 40 out of registry 40 with the dies and to bring a fresh set of blanks into registry with the dies. In the course of the indexing movement one set of completed articles is exposed downwardly, and the mandrels carrying these articles are now subjected to a slight 45 pressure instead of vacuum to blow off the completed articles. In the meantime the empty tray whose blanks have been received by the preceding mandrels of the carriage, is again elevated by elevator 35 in a position to receive the completed 50 articles blown from the mandrels, leaving these mandrels empty. It is at this point that the conveyor chain 15 has its intermittent advance to bring a fresh tray of blanks beneath the empty mandrels for the repetition of the sequence of operations above described. 55

We claim:

1. In a device of the character described for compressing pulp articles, the combination with a cup-shaped die and mandrel receivable therein 60 and slightly smaller in size and rotatably mounted, the angle of the side of the die deviating slightly from the side of the mandrel, of means rotatably supporting the die, said means being pivoted at a point above the mandrel for the lateral swinging movement of the die, and means for laterally swinging said die about the pivotal mounting of its supporting means for the engagement of work on the mandrel, such movement being only sufficient to bring into approximate parallelism the surfaces of the die and the mandrel engaged with such work. 65

2. In a device of the character described for compressing wet pulp articles, the combination with a rotatable die and a rotatable mandrel, and 70 75

means for positively rotating at least one thereof, of a pivoted support for said die upon which said die is movable laterally to bring its inner periphery into engagement with work on the mandrel, means for effecting relative axial movement between said die and mandrel, means for effecting relative lateral displacement between said die and mandrel for the pressure engagement of such work, and vacuum means for holding the work to the mandrel.

3. In a device of the character described for compressing wet pulp articles, the combination with a die member having frusto-conical walls and a mandrel member of complementary form and slightly reduced diameter freely receivable into the die member, of means rotatably mounting said members, means for rotating one of said members, means for laterally displacing one of said members for the engagement of work carried by the other, and means for concurrently effecting relative axial movement between said members to introduce the mandrel member into the die member.

4. In a device of the character described, the combination with an indexing mandrel carriage and sets of mandrels projecting from different sides thereof, of means for the intermittent indexing movement of said carriage, a conveyor running past a station at one side of the carriage, means for the intermittent advance of the conveyor during the dwell of the carriage, means at another station of said carriage for acting on the work carried by the mandrels thereof, and means for automatically delivering the work from the conveyor to the mandrels and subsequently receiving work from the mandrels to the conveyor.

5. In a device of the character described, the combination with a rotatably indexing mandrel carriage having mandrels projecting from its various sides, and means for intermittently indexing said carriage to advance its mandrels from a loading and unloading station to a working station, of conveyor means extending past the loading station, a series of trays movable upon said conveyor means and having work receiving portions registering in said loading and unloading station with the mandrels of said carriage, means for advancing said trays intermittently during the dwell of said carriage, and transfer means for positively delivering the work from the trays to the mandrels during the dwell of said trays and immediately prior to the advance of said carriage, and for receiving the work and delivering it to the empty tray from another set of mandrels following the advance of said carriage.

6. In a device of the character described, the combination with a rotatable mandrel carriage having sides and mandrels projecting in sets from its several sides, of means for the intermittent indexing advance and dwell of said carriage to move said sets of mandrels from a loading and unloading station to a working station and back, die means at the working station and mechanism for actuating said die means to act on work carried by the sets of mandrels at such station, a conveyor means movable past said unloading station and including work receiving pockets, means for the actuation and dwell of said conveyor means in alternation with the actuation and dwell of said carriage, said carriage and conveyor means having overlapping dwell periods, elevator means provided with synchronous operating connections for moving it to and from said carriage during said overlapping dwell periods, said ele-

vator means being adapted to deliver blanks from said pockets to the mandrels of said carriage prior to the indexing of said carriage and to receive work from the mandrels of said carriage subsequent to the indexing thereof, said work being delivered by said elevator means from and to the pockets of said conveyor means.

7. In a device of the character described for the compression of wet pulp articles, the combination with a mandrel carriage having a hollow interior, of tubular mandrel supports projecting from the carriage, mandrels rotatably mounted on said supports and having hollow interiors communicating with interior of the carriage, and ducts extending through said mandrels to the outer periphery thereof, and means for causing the interior of said carriage to vary from atmospheric pressure.

8. In a device of the character described, the combination with a conveyor including tray means provided with pockets, of actuating means for effecting the step by step advance and intervening dwell of the conveyor with respect to a loading and unloading station, a mandrel carrier mounted to rotate on an axis transverse with respect to said conveyor and having mandrels presented toward said pockets in registry therewith at said station, means for effecting the step by step indexing movement and dwell of said mandrel carrier to present successive series of mandrels to successive pockets of said conveyor, an elevator at said station provided with means for advancing and retracting it with respect to said mandrel carrier twice during the dwell of said conveyor, said indexing means being timed to index the mandrel carrier between the successive advances of said elevator, and said elevator being arranged to lift the work in said pockets to the mandrels and to receive from successive mandrels work to be restored to said pockets, and mechanism operable on the first advance of said elevator to subject said mandrels to vacuum to hold the work thereto, and mechanism operative upon the second advance of the elevator to subject said mandrels to pressure for the discharge of work therefrom.

9. In a device of the character described, the combination with a conveyor including tray means provided with pockets, of actuating means for effecting the step by step advance and intervening dwell of the conveyor with respect to a loading and unloading station, a mandrel carrier mounted to rotate on an axis transverse with respect to said conveyor and having mandrels presented toward said pockets in registry therewith at said station, means for effecting the step by step indexing movement and dwell of said mandrel carrier to present successive series of mandrels to successive pockets of said conveyor, an elevator at said station provided with means for advancing and retracting it with respect to said mandrel carrier twice during the dwell of said conveyor, said indexing means being timed to index the mandrel carrier between the successive advances of said elevator, and said elevator being arranged to lift the work in said pockets to the mandrels and to receive from successive mandrels work to be restored to said pockets, and mechanism operable on the first advance of said elevator to subject said mandrels to vacuum to hold the work thereto, and mechanism operative upon the second advance of the elevator to subject said mandrels to pressure for the discharge of work therefrom, together with rotatable dies positioned at another station in the

indexing of said carriage and provided with means for the rotation of said dies in pressure engagement with the work on said mandrels at said last mentioned station.

5 10. In a device of the character described, the combination with a conveyor including tray means provided with pockets, of actuating means for effecting the step by step advance and intervening dwell of the conveyor with respect to a 10 loading and unloading station, a mandrel carrier mounted to rotate on an axis transverse with respect to said conveyor and having mandrels presented toward said pockets in registry therewith at said station, means for effecting the step by step indexing movement and dwell of said mandrel carrier to present successive series of mandrels to successive pockets of said conveyor, an elevator at said station provided with means for advancing and retracting it with respect to 20 said mandrel carrier twice during the dwell of said conveyor, said indexing means being timed to index the mandrel carrier between the successive advances of said elevator, and said elevator being arranged to lift the work in said pockets 25 to the mandrels and to receive from successive mandrels work to be restored to said pockets, and mechanism operable on the first advance of said elevator to subject said mandrels to vacuum to hold the work thereto, and mechanism operative 30 upon the second advance of the elevator to subject said mandrels to pressure for the discharge of work therefrom, together with rotatable dies positioned at another station in the indexing of said carriage and provided with means for the 35 rotation of said dies in pressure engagement with the work on said mandrels at said last mentioned station, said mandrels being also rotatable and said vacuum applying means continuing effective during the operation of said dies.

40 11. In a machine for compressing wet pulp cup-shaped articles, the combination with a cup-shaped die member having a concave interior compression surface and a coacting mandrel member having a convex exterior compression surface, the mandrel member being freely receivable into the die member, of means for rotating one of said members, means for producing relative axial movement between said members in a direction to introduce the mandrel member 45 into the die member, and means for concurrently moving one of said members laterally with respect to the other, whereby to effect the pressure engagement of work between said convex and concave surfaces.

55 12. In a machine for compressing wet pulp articles, the combination with a carriage and a cooperating relatively stationary frame, of a set of hollow die members, a set of coacting mandrel members freely receivable therein, one of said 60 sets being mounted on the carriage and the other upon said frame, means for concurrently rotating the members of one of said sets, means for moving one of said sets of members axially toward the other in a direction to introduce the several mandrel members into the several die members, and means for concurrently moving the members of one of said sets laterally with respect to the complementary members of the other set for the pressure engagement of work 65 mounted on the members of one of said sets.

70 13. In a machine for compressing wet pulp articles, the combination with cup-shaped hollow die members having interior wall portions substantially straight sided in an axial direction and circumferentially concave, of complementary

mandrel members having wall portions substantially straight sided in an axial direction and circumferentially convex, the mandrel members being freely receivable into the die members and the respective wall portions deviating slightly from each other in an axial direction, means for tilting some of said members with respect to the complementary members sufficiently to bring their respective side surfaces into pressure engagement with work and to substantial parallelism with the coacting surfaces of the complementary members, and means for concurrently moving some of said members axially with respect to the complementary members, whereby to progressively introduce the mandrel members 15 into the die members in pressure engagement with the work.

14. In a machine for compressing wet pulp articles, the combination with a frame, of an indexing carriage mounted thereon and a second carriage movable to and from the indexing carriage upon the frame, a set of hollow die members carried by one of said carriages, a set of mandrel members carried by the other carriage, means for indexing the first mentioned carriage 20 to bring its members into registry with the members of the other carriage, means for advancing said other carriage to receive the mandrel members into the die members, means for rotating at least the members of one of said sets while 25 the mandrel members are within the die members, together with means for laterally displacing the members of one of said sets with respect to the carriage upon which they are mounted, whereby to effect lateral pressure engagement of 30 work between the members of the respective sets, and driving connections for the synchronous operation of said lateral displacing means and the advance of the second mentioned carriage toward the indexing carriage, whereby said 35 lateral displacing means will be effective during such advance.

15. In a device of the character described, the combination with a die and a mandrel of differing diameters, of means for rotatably supporting 45 the die and the mandrel with their axes offset for pressure engagement with the wall of a hollow pulp article mounted on one thereof, and means for the power actuation of both said die and said mandrel at differing rates such that their relative 50 peripheral speeds in engagement with such wall will be substantially identical.

16. In a device of the character described, the combination with a die and a mandrel, of means supporting said die and mandrel for rotation 55 upon offset axes for the pressure engagement of the wall of a hollow pulp article between the inner periphery of the die and the outer periphery of the mandrel, means for producing relative axial movement between the die and the mandrel, and mechanical motion transmitting connections between said die and mandrel positively controlling their relative rates of rotation, said connection being adapted to rotate the die and mandrel at approximately the same peripheral 60 speed of contact with the work.

17. In a device of the character described, the combination with a die and a mandrel of differing diameters, of means supporting the die and mandrel for rotation upon offset axes, means for 70 moving the supporting means axially, whereby to encircle with the die the work upon the mandrel for pressure engagement of the work between the inner surface of the die and the outer surface of the mandrel at one side of the man- 75

drel, and means for driving the die and mandrel at approximately the same relative peripheral speeds, whereby neither will rotate appreciably respecting the work.

- 5 18. In a device of the character described, the combination with a die having an inner pressure surface, of a mandrel having a complementary external pressure surface, said mandrel being almost as large as the die in diameter, whereby 10 the die and mandrel are adapted for cooperation with a rolling action to distribute their pressure upon the intervening work, means mounting the die and mandrel for rotation upon offset axes whereby to roll the work between said surfaces, 15 and means for rotating both the die and the mandrel, said means including synchronized driving connections for operating the mandrel

and the die at approximately the same relative peripheral speed, whereby neither of said surfaces will appreciably rub the work.

19. In a pulp pressing machine, the combination of a cup-shaped die and a mandrel slightly smaller in size and freely receivable therein, of means rotatably mounting the die and the mandrel, means for rotating the die, a source of power, and actuating means connecting said source and said die for axially moving the die with respect to the mandrel, and for displacing the die laterally with respect to the mandrel prior to the completion of its axial movement whereby to press mandrel-supported work in the course of such rotation and axial movement. 15

ERNEST HUFF.

ANDREW KEIDING.
